UNITED STATES PATENT OFFICE.

WILLIAM H. HAMMER, OF WASHINGTON COURT-HOUSE, OHIO.

VENDING APPARATUS.

SPECIFICATION forming part of Letters Patent No. 440,029, dated November 4, 1890.

Application filed May 8, 1890. Serial No. 351,014. (No model.)

To all whom it may concern:

Be it known that I, WILLIAM H. HAMMER, a citizen of the United States of America, residing at Washington Court-House, in the county 5 of Fayette and State of Ohio, have invented certain new and useful Improvements in Vending Apparatus; and I do hereby declare the following to be a full, clear, and exact description of the invention, such as will enable others skilled in the art to which it 10 pertains to make and use the same, reference being had to the accompanying drawings, and to letters of reference marked thereon, which form a part of this specification.

15 This invention relates to certain new and useful improvements in coin-controlled vending apparatus.

The object of the invention is to provide an extremely simple vending apparatus by 20 the use of which articles placed on sale may be doled out when a proper coin is placed in the apparatus, the parts being so constructed that should an attempt be made to manipulate the apparatus by the insertion of an im- 25 proper coin the device will be inoperative and the improper coin will not be deposited; and it consists in the construction and combination of the parts, as will be hereinafter fully set forth, and particularly pointed out in the 30 claims.

The invention further consists in the combination of a cam-shaped operating-lever carrying a coin-pusher, together with a rocking lever, which is operated by the coin and pusher to project and retract the delivery-slide.

In the accompanying drawings, Figure 1 is a front view of a vending apparatus constructed in accordance with my invention. Fig. 2 40 is a vertical sectional view. Fig. 3 is a rear elevation, the back of the casing being removed from one of the compartments; and Figs. 4 and 5 are detail views of the slotted plate through which the coin is passed. Fig. 45 6 is a detail sectional view illustrating the employment of one slide in connection with merchandise and change compartments.

A refers to the case, which is of the general configuration of coin-vending apparatus, and 50 is provided with a series of compartments or hoppers for containing merchandise of differ-

ent qualities and values, so that from the apparatus a purchaser may obtain, by depositing the proper coin, cigars, tobacco, confections, or other such articles usually placed 55 on sale in this class of apparatus. The case, as shown, is divided into seven compartments, and is consequently provided with seven cam-shaped operating-levers B and coin-plates C, having slots, as well as seven distinct sets of 60 operating mechanism, which work or operate in the manner to be hereinafter set forth. The front lower end of the casing has a ledge a, upon which the merchandise is deposited when projected by the delivery-slide, and the 65 front portion of the casing is provided with a door A', having a glass panel through which the merchandise may be viewed, and by lowering this door access can be had to the compartments for the purpose of refilling the 70 same. A strap a' extends longitudinally across the frame beneath where the door is hinged, and openings are located beneath this strap, which are protected by curtains or flaps c, said flaps being adapted to swing outward- 75 ly, and by abutting against the bottom of the casing inward movement thereof is prevented.

Each compartment is provided with a rear wall d, which has at its lower end an opening through which a delivery-slide E of proper 80 size is adapted to pass. The depth of the compartments or hoppers A² can be varied according to the particular class of goods they are intended to contain. For instance, those adapted to contain confections or chewing- 85 gum may be comparatively shallow, while those intended to contain larger articles, as chewing-tobacco, cigars, and packages of cigarettes, may be of a greater size both as to width and depth. When the device is in- 90 tended to retail cigars, such compartments may be made of a size to contain a box in which the cigars were originally packed, the end and a part of the top of said box being removed. In connection with the cigar-box I 95 propose to provide the partition-board d, with a block d', and employ a bent plate D, which can be inserted beneath the first layer of cigars. The front member of this plate D will prevent the cigars catching upon each 100 other or becoming disarranged in the box as they are removed therefrom. In retailing or

vending merchandise which is put up in packages and not liable to adhere, this plate may be dispensed with.

The top horizontal wall of the case A has attached thereto a coin-plate C, having a slot e, through which passes the coin-pusher f. The cam-shaped operating-lever B is pivotally secured to the under side of the top of the casing, and it carries a coin-pusher f, which is preferably bifurcated or formed with two members, one of which is slightly longer than the other, and this coin-pusher f is tapered or conical, and is adapted to lie in the central opening g of the slot e when the handle-bar is fully depressed. The handle-bar below its pivotal point has formed thereon a projection or lug b² and a curved extended finger B', which finger is adapted to abut against the upper end of a rocking lever F to manipulate the same in one direction to retract the delivery-slide. The projection b² carries a laterally-projecting pin G', which may be properly bent to contact with the upper end of a spring-bar carrying a bell B³ for sounding an alarm when the cam-shaped operating-lever is moved.

The rocking lever F has its upper face against which the coin abuts grooved, as shown at h, and in the groove the coin will roll when depressed by the coin-pusher f.

The coin-plate C has a slot corresponding in length and width with the coin which is intended to be passed through the same, and an enlarged tapered opening for the reception of the coin-pusher f, and one side of the slot has a vertical recess g², beyond which projects a spring g', which is secured to the coin-plate C, so as to be moved within the recess when the coin is inserted in the slot. This spring g' will bear against the face of the coin so that it will not drop or move freely through the slot, to prevent an improper coin dropping into the coin-receptacle within the case without first being observed by the depositor. The fingers f' and f² of the coin-pusher f are of a distance apart sufficient to admit a coin of proper size and allow the same to be pushed below the plate C.

In front of the upper portion of the rocking lever F is secured an inclined plate I, which will serve to deflect the coins to one side into a coin-receptacle in rear of the partition-board d of the case. The rocking lever may be formed in one piece and extend downwardly to engage with the delivery-slide, or it may be made of two pieces, as shown.

The delivery-slide E may carry a pocket or be formed with an opening, into which the merchandise will pass, and I do not wish to limit myself to any particular form of delivery-slide further than its being so constructed that it will be reciprocated by the rocking lever. The slide is preferably provided within the case with a raised ledge or stop E', which will abut against the partition-board d.

The rear of the apparatus is closed by a

suitable board, which may extend from the base upwardly, and as the operating mechanism occupies but comparatively little space 70 the remainder of the compartment may be used for storing merchandise.

In practice a vending apparatus constructed as herein set forth will be operated as follows: The cam-shaped operating-levers B will 75 be normally depressed, and it will be necessary to elevate the same before the slots in the coin-plates will be exposed, during which operation the bell will be sounded. A proper coin may now be inserted in the slot, which 80 will rest upon the upper end of the rocking bar, and when the operating-lever is depressed the coin is forced against the upper end of the rocking lever to operate the same and project the delivery-slide, which move will 85 pass an article of merchandise from the hopper upon the ledge a, the coin having been guided by the inclined plate I into a coin-receptacle. It will be observed that the delivery-slide will remain projected until the lever 90 is raised, and should any attempt be made to abstract merchandise from the apparatus it is likely the person making the attempt would elevate the lever and sound an alarm. In case an improper coin—as a cent—is inserted 95 in the slot intended to receive five-cent pieces or nickels, it will rest upon the upper end of the rocking lever, and when the operating-lever is depressed said coin will pass into the bifurcation formed in the pushing-finger, and 100 the rocking lever will not be depressed sufficient to either deposit the coin or operate the delivery-slide, and by raising the operating-lever the coin will be projected through the slot by the rocking lever to allow the person 105 to recover the same. It will also be observed that every time the cam-shaped operating-lever is raised the delivery-slide will be retracted to its full extent.

If desirable, one or more of the compartments may carry a double or a bifurcated slide and a single operating-lever. This is intended for such vending apparatus it may be desired to supply with a compartment for making change, one of the merchandise-compartments containing coins, while the other receives merchandise. Thus, if a person having a nickel desires a one-cent purchase, he can deposit the coin in the proper slot and receive therefor one article of merchandise 110 and four pennies, the coin-receiving recess in the slide being gaged accordingly. If desired, the coins intended for making change may be placed in suitable packages or coin-holders. (See Fig. 6, in which E³ is the slide, 115 E' the merchandise-compartment, and E² the compartment for making change.)

Having thus described my invention, what I claim as new, and desire to secure by Letters Patent, is—

1. In a vending apparatus having a coin-plate with a slot, a cam-shaped operating-lever, and a rocking bar, said rocking bar having an upper end against which the coin abuts

- to operate the delivery-slide directly connected with the lower end of the same when a coin is inserted and the operating-lever depressed, substantially as set forth.
- 5 2. In a vending apparatus, an operating-lever having a coin-pusher and projecting finger, and a rocking lever adapted to be thrown in one direction by the coin and in the opposite direction by the finger of the lever, substantially as set forth.
- 15 3. In a vending apparatus, a coin-plate having a slot, and a vertical spring secured in one of the side walls of the slot to bear against the flat side of the coin when introduced vertically, said spring being pressed to one side when the coin is passed through the slot, substantially as set forth.
- 20 4. In a vending apparatus having an opening for coins, an operating-lever B, carrying a coin-pusher f, a curved finger B' below the pivot of said operating-lever, and a rocking lever having an upper end, against which the coin abuts, the finger B' being adapted to engage with the rear upper face of said 25 rocking lever to operate the delivery-slide outwardly by the combined action of the operating-lever and coin and inwardly by the finger of the operating-lever, substantially as set forth.
- 30 5. In a coin-vending apparatus, the combination of a cam-shaped operating-lever having a coin-pusher f, a curved finger B', and a laterally-projecting pin for operating an alarm mechanism, together with a rocking lever F, constructed substantially as shown and connected directly with the delivery-slide, substantially as set forth.
- 40 6. The combination, in vending apparatus, of the delivery-slide-operating mechanism consisting of a cam-shaped operating-lever having a coin-pusher f, a finger B', a rocking lever having the upper end thereof inclined and provided with a groove located immediately below the coin-receiving slot, a 45 coin-plate having a slot which is centrally cut away, and a spring g', intersecting said slot, the parts being organized substantially as shown, and for the purpose set forth.
- 50 7. In combination with a cam-shaped operating-lever B, having a laterally-projecting pin, a bell mounted on a spring-rod, the upper end of said rod being adapted to be engaged by a pin carried by the operating-lever, so as to sound an alarm when the operating-lever is either raised or lowered, substantially as set forth.
- 55 8. In a vending apparatus, a casing having a rear compartment which contains the operating mechanism and coin-receptacle, an operating-lever B, slotted plate, and rocking lever, a deflecting-plate I, located beneath the
- coin-receiving slot, so as to deposit the coin within the coin-receptacle, for the purpose set forth, a rocking lever connected at its lower end directly to the delivery-slide and provided at its upper end beneath the coin-receiving slot with a groove, substantially as shown.
- 65 9. The combination, in a vending apparatus, of the casing having one or more compartments or hoppers for the reception of merchandise, a partition separating said compartment from the operating mechanism, a delivery-slide adapted to be projected by the operating mechanism, the latter consisting of a vertical rocking bar directly connected at its lower end to the slide and having its upper end located to be operated by the coin, substantially as set forth.
- 70 10. In an apparatus for vending merchandise packed in layers in boxes, a compartment having a ledge d', upon which the open lower end of the box will rest, and a plate D, supported by said ledge and adapted to be passed between the layers of merchandise, so as to separate them from each other and hold part of said merchandise against or adjacent to the front portion of the compartment and part of the merchandise permanently in the rear, substantially as set forth.
- 75 11. In a vending apparatus, two adjacently-arranged compartments, respectively adapted for merchandise and change, a single delivery-slide operating beneath both compartments and having a portion designed to receive and contain merchandise and the other portion provided with a gaged recess to receive and contain a predetermined amount of coin, together with a vertical rocking bar connected directly to said slide, and a cam-shaped lever designed to vibrate the bar through the medium of a coin and horizontally project said slide beyond the case of the apparatus, substantially as set forth.
- 80 12. In combination with an apparatus for vending cigars or articles of tobacco in their original packages, said package having one end removed and a portion of the top cut away, leaving the revenue-stamp exposed, the compartment in which the packing-box is placed having a supporting-ledge d' and bent plate D, and an opening through which the article falls, so as to be projected by the delivery-slide, together with slide-operating means, substantially as set forth.
- 85 13. In testimony whereof I affix my signature in presence of two witnesses.
- 90 WILLIAM H. HAMMER.
